WARP LET-OFF DEVICE OF A POWER LOOM

Kyugoro Sakamoto, Hamamatsu, Japan

Application September 26, 1955, Serial No. 536,676

Claims priority, application Japan April 9, 1955

5 Claims. (Cl. 139—108)

This invention relates to improvements in a warp let-off device for a power loom, wherein warp yarns are positively let off at a constant speed by changing the angle of rotation of the warp beam in accordance with the decrease in the number of layers of warp yarns on the beam.

In the usual loom of this type, the rotation of the yarn beam generally depends upon the tension of the warp yarns to be woven, and the yarns are let off at a quicker speed when the tension of the yarns becomes larger. But this let-off means does not give a good result when thin or elastic yarns are woven, because the yarn itself is affected by the tension.

An object of this invention is to provide a let-off device wherein the speed of rotation of the yarn beam depends on the decrease in the number of the yarn layers on the beam, but modified according to a theoretical curve.

Another object of this invention is to provide means adapted to co-operate with said let-off device so as to further modify the speed of rotation of the beam due to accidental changes of tension of the yarns.

A preferred embodiment of the invention is illustrated in the drawings, wherein:

Fig. 1 is a side elevation of a loom having warp let-off device according to the present invention;

Fig. 2 is the same view as that of Fig. 1 on a larger scale, showing the left part of Fig. 1 in detail;

Fig. 3 is a front view looked from the left hand side of Fig. 2;

Fig. 4 is a plan view of the left part of Fig. 1, showing only the upper parts thereof;

Fig. 5 is an elevation taken on line A—A of Fig. 2; and

Fig. 6 is a plan view taken on line B—B of Fig. 2.

In Fig. 1, 1 is the left side frame of the loom, on which the rocking shaft 2, the tappet shaft 3 and the crank shaft 6 are held on bearings. The lay sword 5 is pivoted on the rocking shaft, and is swung by the crank shaft as usual.

In Figs. 1, 2 and 5, a box 10 is secured to the inner side of the side frame, on which are held three spindles 7, 8 and 9, and two arms 11 and 12 are secured to the spindle 7. The arm 11 is connected to a pin 14 at the foot of the lay sword 5 by a connecting rod 13, so that the swing motion of the lay sword 5 is transmitted to the arm 12. On the spindle 8 are secured arms 15 and 16, the former extending forward and the latter downward. The arms 12 and 15 have respectively a slot 12' and 15' along their length, and these slots are almost overlapped. The arm 16 is fixed at the outer end of the spindle 8 and has also a slot 16' along its length, and a scale 90 is provided along the edge of the slot.

A presser shaft is designated by reference numeral 17 and a presser arm 19 is fixed to the shaft, which is forced to turn in the direction *a* by a spring 18 wound on the shaft.

Another arm 20 is secured to the shaft 17. On the inside of the box 10 is provided a sliding plate 21 which can be slid in a guide groove in the wall of the box. A

2

pin 22 provided at the front end of the sliding plate is connected to a pin 92 at the end of the arm 20 by a link 23, so that the plate is pulled by the arm 20 when the presser arm 19 is turned. A curved groove 24 is provided in the sliding plate 21, the profile of the groove being made in the form which is approximately a parabola.

An arm 25 is pivoted on a pin 9, and an idle roller 27 on a pin 26, which is provided on the arm 25, is fitted in the groove 24. The front part of the arm 25 is bifurcated, and a slot 25' is made in that part. The arm 12 and 15 are located between the bifurcated arms and an idle roller 28 passes through a hole which is formed at the crossing point of the three slots 12', 15', and 25'.

On account of this connection, when the arm 12 is rocked through an angle, the arm 15 is also rocked through the intermediary of the roller 28, but the rocking angle of the arm 15 varies according to the position of the roller, while that of the arm 11 is constant.

When the presser shoe 91 turns in the direction *a* due to decrease of the number of the yarn layers and the consequent decrease in the diameter of the roll of yarns, the sliding plate 21 is slid in the direction *b* by the arm 20 so that the arm 25 turns in the direction *c* as the roller 27 is raised along the groove 24, and the rocking angle of the arm 15 gradually increases while the arm 12 is rocking in a definite angle.

A weight lever 29 is secured to a shaft 30 on each side of the loom. A weight 31 is hung at the free end of the lever, and the upper end of the lever is connected by a lever 80 to a link 81 on which a tension pulley 84 is mounted, so that the tension of the warp yarns 102 is affected by the weight as hereinafter described.

A slide bar 33 is connected to the weight lever on the left side at a pin 93 by an adjustable rod 32 providing with a turn buckle. The bar 33 is slidably fitted in a guide 34 fixed to the frame.

Two arms 36 and 37 are secured to a pin 35 at the lower end of the slide bar 33. The lower end of the arm 37 is connected by a rod 39 to a pin 38, which is fitted in the slot 16' and is adjustable in position along the slot (Fig. 2). The arm 36 has a slot 36' and a roller 42 is rotatably fitted in the slot. The roller is provided at the extreme end of a rack 41, which is slidably fitted in a guide 40 fixed to the frame. The rack meshes with a sector 44 which is pivoted on the vertical shaft 43 (Fig. 6).

On the vertical shaft 43 is fixed a worm 45 which gears with a worm gear 48 on a horizontal shaft 46, and the warp beam 4 is rotated by the shaft 46 through gears 49, 50, a shaft 47, gears 95 and 96 (Fig. 3).

A ratchet wheel 51 is horizontally fixed on the shaft 43 at its lower end, and pawls 53 are pivoted on a fan-shape plate 52, which is extended from the boss of the sector 44. An arm 54 is loosely fixed to the shaft 43, and a curved plate 55 fixed at the end of the arm extends close to the periphery of the ratchet wheel 51.

The arm 54 has a rearward extension 54', and is connected to a rod 58 by a pin 57. A bracket 59 is mounted on the frame.

The rod 58 is connected to a foot lever 97 pivoted at the front side of the loom, so that the rod 58 is pulled in the direction *d* if an operator treads on the foot lever, and the curved plate 55 is turned in the direction *e* and enters into the space between the ratchet wheel and the pawls, in order to disengage the latter from the ratchet wheel.

At the upper end of the shaft 43 is loosely fitted a gear 60, which can be turned by a gear 64 on a vertical shaft 98 (Fig. 2). A skew gear 63 is fixed on the shaft 98, and can be turned by a handle 99 in front of the loom through a spindle 61 and a skew gear 62, which meshes with the gear 63.

A clutch piece 65 is slidably but non-rotatably fixed by a key on the shaft 43, and can be coupled with a clutch piece 66 provided on the boss of the gear 60. The piece 65 is held by a forked end of a bell-crank 68 pivoted on the frame by a pin 67, so that the clutch piece 65 couples with the piece 66 when the lower end of the bell crank is pulled in the direction *f*. The upper end of the bell crank is normally raised by the spring 69, so that the clutch pieces are uncoupled and the gear 60 is loosely turned on the shaft 43. A piece 70 is fixed at the end of the bar 58, and the lower end of the bell crank 68 is inserted in an opening in the piece 70, so that when the bar 58 is pulled in the direction *d*, the bell crank is pulled in the direction *f* and the clutch piece 65 is coupled to the clutch piece 66.

On the tappet shaft 3 are provided two cams 71 and 72, and idle rollers 73 and 74 are respectively in contact with the cams 71 and 72 (Fig. 2). The roller 73 is provided at the end of a lever 75 which is pivoted on a bracket 76 of the right side frame 1' by a pin 100. The roller 74 is provided at the lower end of an easing lever 77 which is pivoted on each side of the frame by a stay bolt 78. A roller 79 is held at the upper end of the easing lever 77 so that the roller 79 moves to and fro when the lever is rocked by the cam 72.

The upper arm 29' of the weight lever 29 is connected by a pin 101 to the link 80, which in turn is connected to the lever 81 on each side of the frame as already described. A pair of guide rollers 85 are mounted on the bracket.

An arm 86 is rigidly secured to the shaft 30 (Figs. 1, 2 and 4), and a brake shoe 87 is provided at the free end of the arm. A cylindrical recess is provided in the arm 75 and a piston 88 is slidably fitted therein. Through the piston is extended a bolt 89, and the latter is fixed to the piston at its head, and a spring 90 is provided in the piston pressing the piston head against the brake shoe 87. The pressure of the piston against the shoe can be adjusted by lock nuts 91' fixed on the bolt. As the weight lever 29 is rigidly connected to the arm 86 through the shaft 30, the influence of the weight 31 on the lever 29 is inactive when the shoe 87 is braked by the piston 88.

The operation of this novel loom is as follows.

The lay 5 is swung by the rotation of the crank shaft 6 as usual, and the arms 15 and 16 are rocked through a certain angle according to the position of the roller 28. By adjusting the position of the pin 38, the stroke of the rod 39 can be regulated.

The rocking motion of the arms 37 and 36 slide the rack 41 and turns the ratchet wheel 51 through the sector 44, plate 52 and the pawls 53. The rotation of the ratchet wheel turns the warp yarn beam through the worm gears 45 and 48, spur gears 49, 50, 95 and 96, therefore the warp yarn is positively let off.

While the diameter of the beam yarn is decreased, the presser arm 19 moves in the direction *a*, and the sliding plate 21 moves in the direction *b*, so that the arm 25 turns in the direction *c* by the co-operation of the curved groove 24 and the roller 27. By this means, the roller 28 gradually approaches to the spindle 8, and the rocking angle of the arms 16 increases.

If the tension of the warp yarn 102 accidentally increases, the tension roller 84 is compelled to move rightward in Fig. 1, so that the weight lever 29 turns in the clockwise direction on its pivot, and the rod 32 is raised. While the roller 42 stays at a definite position, the arm 36 raises so as to increase the distance between the pin 35 and the roller 42, so that the travel of the rack 41 is increased while the rocking angle of the arm 37 is substantially unaltered. If the travel of the rack is increased, the angle of rotation of the sector 44 is increased, so that the rotating angle of the ratchet wheel 51 is increased. By this means the rotation of the yarn beam is increased, and the tension of the warp yarn is moderated.

On the contrary, if the tension of the warp yarn is slackened, the rod 32 is lowered and the travel of the rack 41 is decreased so that the speed of rotation of the ratchet wheel is decreased and the normal tension of the yarn is recovered.

When the loom is not in operation, the yarn beam can be turned by a handle. In such a case the foot lever 97 is trod, and the arm 54 is turned in the direction *e*, and the plate 55 disengages the pawls from the ratchet wheel allowing the latter to be freely turned. At the same time, the piece 70 pulls the lower end of the lever 68 in the direction *f*, so that the clutch piece 65 is coupled with the piece 66. Then the handle 99 can be turned in any required direction, and the vertical shaft 43 is turned through the worm gear 62 and 63. Thus, the yarn beam can be turned in any direction.

When the operation of the loom stops, the crank pin 103 always takes the position, due to balance of the working parts, at an angle of about 80 degrees on the upper part of the circle. In case the crank pin is in this area, the cam 71 takes the position which enables it to brake the arm 86, so that the yarns on the tension roller 84 are not affected by the weight 31, while the loom is not in operation.

The length of yarn to be let off during one rocking motion of the lay can be adjusted by changing the position of the pin 38. To facilitate the adjustment, the scale 90' is provided along the edge of the slot 16'.

According to this invention, the rotation of the yarn beam is effected by the rocking motion of the lay, and the angular velocity of the yarn beam gradually increases while the number of the layers on the beam, and thus the diameter of the beam, decreases. This change of angular velocity is determined by the rising speed of the pin 28 along the arm 12, and its rising speed is controlled by the curved groove 25'. Therefore the let off speed of the warp yarn can be maintained constant throughout the operation if the profile of the curved groove is made in the form of which is approximately a parabola.

If an undue tension on the warp yarns for any reason, the travel of the rack 41 is automatically increased or decreased by the motion of the weight lever, and the speed of rotation of the ratchet wheel is increased or decreased so that the normal tension of the warp yarns is recovered.

What I claim is:

1. A warp let-off device for a power loom having a loom lay, a yarn beam, and a weight lever carrying a weight for tensioning the warp yarn, said device comprising three arms each pivoted on the loom and each having a slot therein, said arms being crossed at a common crossing point, a pin through said slots at the common crossing point, the first of said arms being connected to the loom lay for receiving the rocking movement of the lay, a plurality of pawls pivoted on the loom to which the second of said arms is connected, a ratchet wheel on the loom engageable by said pawls for driving the yarn beam on the loom, a member having a curved slot movably mounted on the loom, a roller on the third of said arms engaged in said curved slot, and a presser shaft pivoted on the loom with one end connected to said member and the other end pressing on the yarn beam, whereby a change in diameter of the yarn beam permits the presser shaft to pivot and move said member, thus moving said third arm.

2. A warp let-off device as claimed in claim 1 in which the connection of the second of said arms to said pawls comprises a slide bar connected at one end to the weight lever, the other end of said slide bar having two extensions thereon, a connecting rod connecting one of said extensions to the second of said arms, a rack connected to the other of said extensions, and a gear sector on which said pawls are carried pivoted on said loom concentric with said ratchet wheel and engaging said rack.

3. A warp let-off device as claimed in claim 1 in which said member having the curved slot therein is a plate

slidably mounted on said loom, said plate being connected to said presser shaft by a link pivoted to said plate and secured to said presser shaft.

4. A warp let-off device as claimed in claim 1 in which said curved slot has a curve approximating a parabola.

5. A warp let-off device as claimed in claim 1 further comprising an arm pivoted on said loom, an idler roller at the free end of said arm, a tappet shaft rotatably mounted on the loom, a cam on said tappet shaft on which said idler roller rolls, said arm having a cylinder therein, a resilient piston in said cylinder, a post on the weight lever at the fulcrum thereof, a brake shoe on the end of said post against which the head of said piston bears,

whereby when said cam lifts said arm, said piston bears on said brake shoe to brake the pivoting of the weight lever.
